(57) **CLAIM**

The ornamental design for decorative ornament, as shown and described.

DESCRIPTION

The patent or application file contains at least one drawing executed in color. Copies of this patent or patent application publication with color drawing(s) will be provided by the Office upon request and payment of the necessary fee.

1. Decorative ornament

3. Decorative ornament

1.1 is a top, right perspective view of a full color decorative ornament embodying my new design;

1.2 is a front elevation view thereof;

1.3 is a left side elevation view thereof;

1.4 is a rear elevation view thereof;

1.5 is a right side elevation view thereof;

1.6 is a top plan view thereof;

1.7 is a bottom plan view thereof;

3.1 is a top, right perspective view of a second embodiment of a monochrome decorative ornament;

3.2 is a front elevation view thereof;

3.3 is a left side elevation view thereof;

3.4 is a rear elevation view thereof;

3.5 is a right side elevation view thereof;

3.6 is a top plan view thereof; and,

3.7 is a bottom view thereof.

(Continued)

If present, the broken line shown is for the purpose of illustrating portions of the decorative ornament and forms no part of the claimed design.
